Int. Cl. D9—05

U.S. Cl. D9—249

FIG. 1 is a bottom perspective view of a combined bag and information containing pocket showing my new design; and

FIG. 2 is another bottom perspective view showing the side opposite that seen in FIG. 1.

The dash lines indicate score lines.

The characteristic features of my design reside in the specifically positioned and outlined information containing pocket on the bottom of a bag all as shown.

I claim:

The ornamental design for a combined bag and information containing pocket, as shown and described.
